UNITED STATES PATENT OFFICE.

SILAS M. FORD, OF ST. PAUL, MINNESOTA.

ROOFING.

1,209,955.

Specification of Letters Patent. Patented Dec. 26, 1916.

Application filed February 21, 1916. Serial No. 79,608.

To all whom it may concern:

Be it known that I, SILAS M. FORD, a citizen of the United States, residing at St. Paul, in the county of Ramsey and State 5 of Minnesota, have invented certain new and useful Improvements in Roofing.

This invention relates more specifically to a type of shingle or shingle strips made of prepared roofing and adapted to be laid on 10 a roof in the same manner as the ordinary wooden shingle.

One object of my invention is to provide in a shingle a stop or dam at approximately the point at which the shingles will lap, so 15 that rain cannot be driven up between the shingles.

Another object of my invention is to provide a lock on the top end of the shingle adapted to register with the lock and dam formed in the central portion of the shingle below.

Another object of my invention is to provide a nailing point for laying shingles on a roof in such manner that the nail will 25 pierce the dam or lock, passing through an unusual number of thicknesses of shingle material, and at the same time be covered from exposure to the weather by the butt of the shingle above.

Another object of my invention is to provide at the butt end of the shingle a downwardly turned projection that will prevent the wind from getting under the butt of the shingle and tend to lift it from the roof.

Another object of my invention is to provide in double shingles or shingle strips a slot or slots in the lower half of the shingle to preserve the appearance of unit shingles, and in the upper half of the shingles a rec- 40 tangular aperture in the same line as the slots, so that the slots and the aperture will serve as expansion points for the shingle strip, and a tongue portion of the shingle may be folded over to seal the aperture in 45 the upper half.

Another object of my invention is to provide in a double shingle or shingle strip a slot in the lower half of the shingle to preserve the appearance of unit shingles, with 50 a marginal strip running transversely of the shingles at the lower end, to strengthen or hold together the tabs formed by the slots, in such a manner that this strip will not

serve to dam water that might be running down the surface of a roof covered with the shingle strips.

Another object of my invention is to provide a nailing point close to the butt to strengthen the shingles against being lifted by the wind, the nailing point comprising 60 also a reinforcing cleat for the shingle below, and serving as a gage line for laying the shingles.

With these and incidental objects in view the invention consists of certain novel features of construction and combination of parts, the essential elements of which are hereinafter described with reference to the drawings which accompany and form a part 65 of this specification.

In the drawings, Figure 1 is a plan view of my improved shingle. Fig. 2 is a side elevation of the same. Fig. 3 is a side elevation of a portion of a roof laid with this type of shingle, and Fig. 4 is an enlarged 75 cross-sectional detail to show the method of nailing. Fig. 5 is a plan view of an alternate construction of my shingle, and Fig. 6 is a side elevation of the same. Fig. 7 is a side elevation of a portion of a roof laid 80 with this type of shingle. Fig. 8 is a plan view of a still further modification of my shingle, and Fig. 9 is a side elevation of the same. Fig. 10 is a side elevation of a portion of a roof laid with this modified type 85 of shingle. Fig. 11 is a plan view of a double shingle or shingle strip embodying my invention, and Fig. 12 is a side elevation of the same. Fig. 13 is a perspective view of a modified type of double shingle 90 embodying my invention, and Fig. 14 is a side elevation of a portion of a roof laid with this type of double shingle. Fig. 15 is a perspective view of a modification of the shingle strip shown in Fig. 13, and Fig. 95 16 shows a development of the portion of the shingle strip shown at "A", Fig. 15.

It will be seen from Figs. 1 and 2 that the butt of the shingle 1 is plain, while the top 2 has a return fold extending transversely 100 across it, and there is also a Z shaped fold 3 substantially at the center of the body of the shingle extending transversely thereof.

Figs. 3 and 4 show that when the shingles are laid on a roof, there will be at the nailing points along the Z shaped fold five 105

thicknesses of the material for the nail to penetrate, while the butt 1 of the shingle above will cover the heads of the nails used in fastening the shingles, also the fold 3 locks in the fold 2 of the shingle below, forming substantially a cleat extending across the shingles at the central portion thereof. It is also apparent that the fold 3 serves as an absolute dam against water being blown up under the shingles on the shingle itself, and the fold 3 taken in conjunction with the fold 2 of the shingle below, forms a complete dam against water getting in between shingles in what is ordinarily known as the gutter, and being blown up under the shingles.

In order to make a better looking butt on the shingles after they are laid, I bend the lower edge of the butt 4, Figs. 5 and 6, at substantially right angles to the butt, so that the bend so formed extends down over and covers the joint between folds 2 and 3 when the shingles are laid, as plainly seen in Fig. 7.

As a further protection against wind or rain getting in between the shingles, I provide an extension 5 at the top of the shingle at the fold 2, Figs. 8 and 9, thus giving a longer lap at the point 6, as plainly shown in Fig. 10.

In double shingles or shingle strips, I cut a slot 7, Fig. 11, this slot being spaced equally in shingle strips, and it is evident that the folds 2 and 3, Figs. 11 and 12, will form a dam that will absolutely prevent water passing up under the slots as shown, equally as well as with the plain shingles heretofore described, and the slots will serve also to take up the expansion in the lower part of the shingle strip. As a still more effective means for taking up expansion, I sometimes shear a tongue 8, Fig. 13, from the double shingles or shingle strips, leaving a slot 7 and fold this tongue back tight against the upper part of the shingle to cover the slot 9 punched out of the upper half of the shingle, the two slots 7 and 9 thus serving to take up the expansion in the body of the shingle, except the folds themselves, which being heavier and comprising the nailing points for the shingles are better able to take care of the expansion than the remaining portion of the shingle strips.

In Fig. 13, the tongue 8 is slightly lifted from the top of the shingle, in order to better disclose the slot 9, but in practice this would be pressed down tightly against the slot. Similarly, in Fig. 15 I show a method of reinforcing the tabs formed in the lower half of the shingle, in the style shown in Fig. 13. These reinforcements comprise a longitudinal strip 10, Fig. 15, at the lower edge of the butt of the shingle, the slot in this case being cut out of the body, but extending to the butt of the shingle. It will

be noted, however, that the lower half of the slot extends down below the folding line 11, Fig. 16, of the reinforcing strip, so that when this is folded over and serves as a facing to cover the joints 2 and 3, similar to the fold 4, Figs. 5 and 6, any water in the gutter formed by the slot 7, Fig. 15, will run freely out of the lower end of the slot 7, as there will be no portion of the strip 10 projecting above the surface of the bottom of the gutter.

The surface of the shingles made from prepared roofing stock is preferably covered with some kind of mineral coating, such as mica, slate, etc., and my improved shingle lends itself to this construction. In the case of the shingles shown in Figs. 1 and 2, the surface below the line 12, Fig. 1, may be coated with mineral coating, while the surface above will be free of mineral coating, and in all of the variations shown, the shingle or shingle strip would preferably be surfaced in this manner.

I prefer to use for my shingle a water-proofed fibrous material, which is made from the fibrous material by impregnating it with a water-proofing compound, the surplus of which is all squeezed from the stock, the upper face of the material is then given a heavier coating of a weather-proofing compound, and such portions as are to be exposed to the weather preferably covered with a mineral surfacing. With a shingle made from such stock, the surfaces 20 and 21 will have the weather-proofing compound thereon, which is of a very tacky nature, while the surfaces 22 and 23 will have only the water-proofing compound, which has been squeezed out of the stock, so that very little is on the surface, and hence these surfaces 22 and 23 are of a much less tacky nature. The surfaces 24 and 25 have the weather-proofing compound thereon, and are therefore tacky, and for shipping purposes I prefer to cover these surfaces with a talc powder.

When the shingle is finished the fold 3 will be pressed tightly, and hence the surfaces 20 and 21 will amalgamate together on account of their tacky nature, whereas the surfaces 22 and 23 will not so amalgamate, and the upper portion of the shingle can swing about the junction of surfaces 21 and 23, as a hinge. The fold 2 is not pressed tightly in manufacture, and as a certain amount of talc powder is used these surfaces will not adhere tightly.

In laying shingles, the first row would be nailed through the fold 3, and the shingles to form the second row would be slipped into the fold 2 of the first row, the upper portion of the shingle being bent forwardly at the free hinge joint of the fold 3, so as to facilitate laying of the shingles. Then the row would be tacked through the fold 130

3, as plainly shown in Fig. 4, and the next row added thereto. It is apparent that this greatly facilitates the laying of the shingles, and as the surfaces 24 and 25 of the lower shingle are joined with surfaces 22 and 26 of the shingle next above, and the joint so formed nailed through the tackiness of the surfaces 24 and 25, under the nailing pressure will cause the surfaces to amalgamate.

10 While I have described my invention and illustrated it in several designs, I do not wish it understood that I limit myself to these constructions, as it is evident that the application of my invention may be varied 15 in many ways within the scope of the following claims:

1. As an article of manufacture a double shingle or shingle strip having a fold running transversely thereof, at substantially the center thereof, slots running longitudinally thereof in the lower half of said double shingles or shingle strips, a tongue formed by the cutting of said slots being bent back toward the upper portion of said double shingles or shingle strips, a series of rectangular apertures in the upper half of said double shingles or shingle strips adapted to be covered and closed by the tongues bent backwardly toward the top of said double shingles or shingle strips.

2. As an article of manufacture a double shingle or shingle strip having a fold running transversely thereof at substantially the center thereof, slots running longitudinally thereof in the lower half of said double shingles or shingle strips, a tongue formed by the cutting of said slots being bent back toward the upper portion of said double shingles or shingle strips, a series of rectangular apertures in the upper half of said double shingles or shingle strips adapted to be covered and closed by the tongues bent backwardly toward the top of said double shingles or shingle strips, and a reinforcing strip running transversely along the butt of said double shingle or shingle strip for reinforcing the tabs formed by said slots in the lower half of said double shingle or shingle strips, said reinforcing strip being formed downwardly at an angle of substantially 90 degrees with said double shingles or shingle strips, said longitudinal slots extending into said reinforcing strip a distance substantially equal to the thickness of the stock of said reinforcing strip.

3. As an article of manufacture a shingle strip formed of water-proofed material having a dam running transversely across said shingle strip at approximately the point where the butt of the shingle above will be positioned when laid shingle fashion on a roof and having a strip along the top thereof folded back toward the top surface of said shingle strip, said dam and said fold being so positioned that the fold on one shingle

strip will lock with the dam of the shingle strip superimposed above, and the dam and the folded strip being surfaced with a tacky surfacing.

4. As an article of manufacture a shingle or shingle strip having a dam formed by a transverse fold of said shingle or shingle strip intermediate of the top and bottom of said shingle or shingle strip, the fold of said dam being so positioned that the dam of one of said shingles or shingle strips will register and lock with the folds of a shingle or shingle strip placed above when laid upon a roof, and said dam and said fold having the top surface of the shingle forming said sub-dam and said fold coated with a tacky substance.

5. As an article of manufacture a shingle or shingle strip having a fold running transversely intermediate of the ends thereof, the material forming said fold being coated with a tacky substance, and a strip running transversely along the butt thereof formed downwardly at substantially 90 degrees with said shingle or shingle strip.

6. As an article of manufacture a shingle or shingle strip having a Z shaped fold at substantially the center of said shingle or shingle strip, a second Z shaped fold running transversely along the top of said shingle or shingle strip, the material of which said shingle or shingle strip is formed being coated with a tacky substance at that portion of the top surface wherein said Z shaped folds are formed.

7. As an article of manufacture a shingle strip having a dam formed by a transverse fold of said shingle strip intermediate of the top and bottom thereof, a strip along the top of said shingle strip folded backwardly toward the top surface thereof, said dam and said fold being so positioned that the dam of one of said shingle strips will register and lock with the fold of a shingle strip placed above when laid upon a roof shingle fashion, and said dam and said fold having the top surface of said material forming said dam and said fold coated with a tacky substance.

8. As an article of manufacture a shingle strip having a dam formed by a transverse fold of said shingle strip intermediate of the top and bottom of said shingle strip, that portion of the fold of said dam wherein two portions of the top surface of the original strip come together, being pressed tightly and amalgamated, and that portion of the fold forming the dam where two portions of the back surface of the original strip tend to come together being left free to swing as a hinge.

9. As an article of manufacture a shingle strip having a dam formed by a transverse fold of said shingle strip intermediate of the top and bottom of said shingle strip, that

portion of the fold of said dam wherein two portions of the top surface of the original strip come together being pressed tightly and amalgamated, and that portion of the 5 fold forming the dam where two portions of the back surface of the original strip tend to come together being left free to swing as

a hinge, and having a strip along the top thereof folded back toward the top surface of said shingle strip and adapted to amalgamate with the back surface of the fold forming the dam of a similar shingle laid thereon shingle fashion. 10

SILAS M. FORD.
